James B. Wright, Philadelphia, Pa.

Application June 5, 1950, Serial No. 10,367

Term of patent 14 years

(Cl. D57—1)

To all whom it may concern:

Be it known that I, James B. Wright, a citizen of the United States of America, residing at Philadelphia, in the county of Philadelphia and State of Pennsylvania, have invented a new, original, and ornamental Design for a Spectacle Frame or Similar Article, of which the following is a specification, reference being had to the accompanying drawing, forming part thereof.

Figure 1 is a top plan view of a spectacle frame or similar article, showing my new design;

Fig. 2 is a side elevational view thereof; and

Fig. 3 is an inside elevational view of one of the temples shown in Figs. 1 and 2.

The essential features of my design reside in the temples shown in full lines and which are characterized by their specific configuration and

shortness so as to grip the sides of the face of the wearer and not to extend rearwardly over the ears of the wearer.

I claim:

The ornamental design for a spectacle frame or similar article, as shown and described.

JAMES B. WRIGHT.
